UNITED STATES PATENT OFFICE.

DUANE PHIMISTER, OF CHICAGO, ILLINOIS.

CARD DECK.

Application filed August 15, 1925. Serial No. 50,486.

To all whom it may concern:

Be it known that I, DUANE PHIMISTER, a citizen of the United States, and a resident of Chicago, in the county of Cook and State 5 of Illinois, have made a new and useful Invention in Improvements in a Card Deck, of which the following is a specification.

The invention relates to a card deck. It has for its object the provision of a deck, 10 which may be used to play a number of interesting and instructive games, all of which include the feature of building words, which gives the games an educational value. The deck is preferably made up of fifty-two 15 cards, each of which carries upon its face two letters, which are printed on backgrounds of two different colors, although the same result might be achieved by having the background all of one color with the two 20 letters in different colored ink. The two letters on each card are what may be termed "dial opposite" letters, that is they are, in each case, the letters which lie at 180 degrees from each other when the alphabet is 25 arranged in an annulus with the letters spaced apart at equal intervals. The deck, therefore, contains four complete alphabets, which are employed in word building, as later explained. The character of the cards, 30 and the dial opposite feature, will be apparent by reference to the accompanying drawings, wherein:

Figure 1 is a face view of one of the cards. Fig. 2 shows a card with the same letters as Fig. 1, but with a different color arrangement, and Fig. 3 is a diagram showing the dial opposite arrangement of the letters which governs the two letters which are applied to each card.

By reference to the card illustrated, it will be noted that it bears the letters A and N, which come opposite each other on the dial of Fig. 3. Similarly, the letters B and O would appear on another card, B and O being dial opposite as is the case of A and N. This arrangement obtains throughout the deck. In the particular color arrangement selected for illustration, the letters A and N are in white, the letter A being upon 45 a black background, while the letter N is upon a red background. In the card shown in Fig. 2, an equivalent arrangement is shown, the background of both letters being white with letter A in black ink and the 50 letter H in red ink. A variety of other color schemes might be employed to secure the

two different color designations for the letters at the opposite ends of the cards, the term "color designation," as used in the claims, being intended to cover color indicating means for the letters in whatever form applied.

A large number of different games may be played with the deck, but a brief explanation of one simple game will be described to 60 indicate the general principle of the game, which has been named "hodag," and the method of play.

The game is designed for use by from two to eight players. After a table is made up, 70 the cards are cut to the right and dealt to the left in rotation until each player has five cards. Upon starting the deal, the dealer makes the agreed-upon ante. After observing their cards, players may come in or pass. 75 A pass before the draw is a pass out.

Each player who stays is privileged to draw, as he may elect, from one to five cards to help his hand, discarding face down a 80 number of cards equal to his draw, before he picks up the draw. Cards discarded are gathered into a pile from which cards may be supplied to complete the draw if the undealt portion of the deck runs short. This will usually happen only when seven or eight are 85 playing.

The hands in hodag are words. There are three classes. A word of three letters is called, a Trip, a word of four letters, a Quart, and a word of five letters, a Quint.

Bidding and raising before and after the draw may continue until all hands are called.

In each class, words may be constructed with all letters in the red, such words being 95 Yes words; with all letters in the black, such being No words or with part of the letters in the black and part in the red. A word with one off-color letter is called an Off and one with two off-color letters is called a 100 Dub. There are no Dub-trips. A Dub-quart is regarded as in the red, when its first letter is red and as in the black when its first letter is black.

In general, Quints beat Quarts and 105 Quarts beat Trips but, as explained in cancellation rules below, there are special cases in which Trips beat Quints. Yes words beat No words of same rank; No words beat Offs and Offs beat Dubs.

If two words of equal rank and class are spread for the pot the word most advanced

in the alphabetical sequence wins. Thus the Yes-trip "VAN" wins over the Yes-trip "USE," because "V" is more advanced than "U," and the No-quint "WHITE" wins over the No quint "WHEEL" because "I" is farther advanced in the alphabetical sequence than "E."

The called hand must spread first and other contestants in the pot in their order of 10 play, beginning with the spreader. A Quint spread for the pot may be beaten by a subsequently spread Trip, if the Trip can cancel the Quint under the following rules.

A Yes-quint can be cancelled only by 15 a No-trip, a No-Quint only by a Yes-trip. Off or Dub-quints can be cancelled by an Off-trip of the opposite color.

In order to cancel, the Trip must show as 20 its first letter the dial opposite and color opposite letter of the first letter of the Quint that is under cancellation. Thus, the No-trip "NOW" will cancel and win over the Yes-quint "ALONE," because "N" in the black is the dial and color opposite of "A" 25 in the red.

Off and Dub-quints can be cancelled by Off-trips of the opposite color.

Yes or No Quints the first letter of which is repeated in the Quint cannot be cancelled.

If two Trips are spread to cancel a Quint, 30 the Trip most alphabetically advanced wins.

If after a Quint is spread and cancelled by a Trip, another contestant for the pot still having the right to play in his order can spread a Quart he wins over the cancelled Quint, and the cancelling Trip. 35

What I claim is:

1. As a new article of manufacture, a card deck containing the letters of the alphabet in which each card bears two different letters, one letter of each card having one color designation and the other letter another color designation. 40

2. As a new article of manufacture, a card deck containing the letters of the alphabet in which each card bears two different letters, such letters in each case being dial opposite, and having different color designations. 45

In testimony whereof I have hereunto subscribed my name this 12th day of August, 50 1925.

DUANE PHIMISTER.
